UNITED STATES PATENT OFFICE.

LOUIS A. M. PHELAN AND CLIFFORD HOTCHKISS, OF BELOIT, WISCONSIN; SAID HOTCHKISS ASSIGNOR TO SAID PHELAN.

ELECTRICAL APPARATUS.

Application filed November 24, 1922. Serial No. 603,027.

Our invention relates to electrical apparatus and it has special reference to electrical contact-making devices comprising spaced electrodes that are sealed into a closed container and are adapted to be brought into electrical conducting relation with one another through the agency of a movable conducting body, preferably a fluid such as mercury, likewise disposed in said container and which, on being tilted, is instrumental in performing the circuit-closing and circuit-opening functions of the device.

More particularly our invention refers to an electrical contactor device of the character indicated above, which will operate for long periods of time and serve to make and break comparatively large amounts of current without deterioration in any of its parts.

Our present invention pertains to an electrical contactor device, as described above, which, if desired, may comprise a cylindrical elongated tube, preferably in the form of a glass container, that serves to house electrodes and a body of conducting fluid such as mercury, the latter being adapted to bridge the electrodes within the tube. The tube is preferably disposed when installed, to occupy normally a position neighboring on the horizontal and is suitably supported so that it may be tilted in either direction and thus allow the conducting fluid to flow into and out of circuit-making position at the expense of very little energy. The electrodes are sealed within the tube, and as shown in this particular instance, are adjacent to each other to form a cooperating pair. As shown, it will be noted that the leading-in wires to the electrodes enter the glass container at points spaced considerably distant or remote from the electrodes themselves.

A particular object of our present form of construction of contactor devices is that it enables the contact members to be spaced a considerable distance from the points where the leading-in wires are sealed in the glass container, thus avoiding the undesirable effects due to the heat of the arc at the contacts and its effects upon the leading-in wires and adjacent glass.

A further object of this invention is to provide a particular spacing of the electrodes in relation to each other, to the container and to the body of conducting fluid

in order that the usual deterioration of the electrodes by arcing will be avoided.

A further object of this invention is to provide a contactor device of the type indicated above that will be simple and economical to construct and which will possess a long life even when subjected to considerable quantities of electric current at substantial voltages.

Further objects will appear upon reference to the following description and accompanying drawings, in which—

Figure 1 is a vertical sectional view of one modification of device embodying our invention;

Fig. 2 is a sectional view taken on line 2—2 of Fig. 1, looking in the direction of the arrows;

Fig. 3 is an enlarged detail view of the electrodes and mercury, showing the position of the mercury when about to come into circuit-closing position;

Fig. 4 is another enlarged detail view of the electrodes and mercury, showing the position of the mercury when in contact with both electrodes;

Fig. 5 is a view similar to that in Figs. 3 and 4, but showing the position of the mercury when about to move to open circuit position;

Fig. 6 is a detail perspective view of one form of electrode;

Fig. 7 is a vertical sectional view of a modification of device embodying our invention, and

Fig. 8 is a sectional view taken on line 8—8 of Fig. 7, looking in the direction of the arrows.

Referring to Figs. 1 and 2, the device preferably comprises in a general way a cylindrical and elongated tube 11 made preferably of glass, housing a pair of cooperating electrodes or contact members 12 and 13, shown located at one end of the tube and which are spaced from each other and are adapted to be bridged by a body of mercury 14, which is likewise housed in the tube 11. The tube 11 when constructed is first evacuated and then filled with a gas such as hydrogen, which is inert under the action of an electric arc in the presence of the mercury and electrodes. This gas may be at substantially atmospheric pressure and serves to minimize arcing and vaporization of mer-

cury in the tube as well as deterioration of the tube. The absence of air and its oxygen in the tube, eliminates all possibility of oxidation of the mercury and electrodes.

- 5 It will be observed from the drawings that if the tube 11 should be tilted in the proper direction, the body of mercury 14 will flow toward the electrodes 12 and 13, thus bridging the electrodes, thereby placing them into electrical conducting relation with each other. The electrodes 12 and 13 are made of suitable material, such as pure iron, or other conducting materials that do not suffer deterioration under the conditions obtaining, and are supported respectively on connecting leads 15 and 16, also preferably composed of a similar metal. The use of iron is desirable in that this metal does not become amalgamated. The leads 15 and 16 20 may be integrally formed with electrodes 12 and 13, or if desired, the cores of the leads may be made separate as at 15^a in Fig. 6 and also of metals other than those named above, in which latter case they should be covered 25 or plated with a sleeve 15^b composed of one of the pure metals named above, in order to avoid any interaction of the mercury or vapor in the tube with the core or any impurities therein.
- 20 The leads 15 and 16 are supported respectively on glass shanks 17 and 18, which extend down from the end walls of and are formed integrally with the glass chambers 19 and 20, respectively, at the ends of the 35 tube 11. Leading-in wires 21 and 22 made of Dumet wire, because of its desirable expansive properties and its tendency to unite with glass when sealed into glass, provide means for connecting the leads 15 and 16, 40 respectively, in an external electrical circuit. The leading-in wires are joined to the leads 15 and 16 at joints 23 and 24, respectively, at the inner end of and preferably slightly within the glass shanks 17 and 18 and hence 45 the Dumet wire is at no place exposed in the interior of the tube. The joints 23 and 24 are preferably very near the ends of the glass shanks 17 and 18 so that the expansion or contraction of the leads 15 and 16 will not 50 unnecessarily strain the glass. The leading-in wires 21 and 22 may be connected, respectively, to flexible leads 25 and 26, or to other suitable connecting members of the exterior circuits.
- 55 The tube 11 is evacuated, filled with hydrogen and sealed off by means of a tip 27.

The seals to the Dumet wires 21 and 22 and glass shanks 17 and 18 are located at the extreme ends of the tube in the modification of Figs. 1 and 2 and at a distance from the electrodes. The glass chambers 19 and 60 65 serve the double purpose of furnishing a larger radiating surface and of enclosing and supporting the glass shanks 17 and 18, which can thus be made of sufficient length

to rigidly support and seal the wires 21 and 22 and still not extend into the main portion of the tube. The glass shanks in former structures have been constructed to extend into the main portion of the tube where they 70 tend to interfere with the free flowing of the mercury and also are exposed to the heat of the arc at the contacts. Our present type of construction also permits the use of leads 15 and 16 of considerable length. Leads of 75 this length permit the greater part of the heat of arcing to be radiated before it can possibly be conducted to the glass shanks 17 and 18. The small amount of heat that is conducted to these shanks is not subject to 80 any rapid fluctuations and is insufficient to result in any damage to the glass.

It will be observed that the supporting shanks 17 and 18 and the glass chambers 19 and 20 in this structure are located at the 85 upper side of the tube at points well out of the way of the mercury 14 and the arcing at the electrodes 12 and 13, so that in the normal operation of the tube the mercury does not come in contact with the surfaces of 90 these glass parts and thus all possibility of the gathering of a conducting coating on these parts is avoided or greatly minimized.

A form of the electrode that may be used at 12 and 13 is shown in detail in Fig. 6. It 95 will be noted that the electrode comprises a considerable volume of material. The object of this larger volume of material in comparison to the size of the lead wires is for the purpose of absorbing as much as 100 possible of the heat generated at the electrodes, due to the arcing that occurs when the circuit is open or closed. A further object of these large electrodes is to insure ample contact area. It will be noted in Fig. 6 105 that the end of the electrode is slightly rounded at 12^a. The use of flat surfaces on these electrodes has been avoided in order to avoid undesirable sticking of the mercury to the electrode. It has been found that 110 where plain surfaces have been used on the electrodes that the mercury has a great tendency to stick to such surfaces after use of the devices for a short time. The rounded surfaces tend to avoid the tendency of the mercury to create a vacuum between itself and the electrode when the two are being separated and that hence the avoidance of this vacuum does away with the difficulty of sticking. When the tube is tilted to only a 115 120 relatively slight angle, the flow of the mercury can be very easily retarded or stopped. It has even been found that a slight contamination of the mercury by any impurities will render the mercury sufficiently sluggish to prevent its proper operation at such slight angles.

It is very desirable that the electrode be made in substantially the cylindrical form 125 shown since the rounded surfaces offer very 130

little resistance to the natural flow of the mercury and also avoid the creation of troublesome vacuum spaces which occur between flowing mercury and flat metallic surfaces and result in checking the flow of mercury.

It will be noted that the electrode 13 is placed nearer the center or mid-portion of the tube 11 and at a slightly greater elevation than the electrode 12. It will be noted that both of the electrodes are placed in a position such that no part of the glass container is directly exposed to the arc. The movement of the mercury in the process of making and breaking the circuit will now be outlined in order to bring out clearly the advantages of this particular positioning of the electrodes. As the tube is slowly tilted in the proper direction, the mercury 14 will slowly flow toward the electrode 12, the electrode 13 being in a slightly higher plane is not at first touched by the body of mercury 14. As the mercury flows around the electrode 12, the surface of the electrode will become wetted by the mercury and the consequent capillary action will draw the mercury around the lower portion of the cylindrical surface of the electrode as appears in Figs. 3, 4 and 5. The position of the body of mercury 14 at this instant is shown in Fig. 3. As the tube becomes slightly more tilted, the mercury will rest partly against the end of the container 11. This will cause the flow of the mercury to back up to some extent and the body of mercury 14 will then become sufficiently deep to alter its shape to touch the electrode 13. As the mercury approaches the electrode 13, it will be quickly drawn into full contact-making position because of the capillary action similar to that occurring at the electrode 12. This action will be very materially aided by the mercury wetted surface 13, this mercury wetted surface having been formed by previous contact with the body of mercury 14. If any slight arcing occurs as the mercury approaches the electrode 13, this arcing will be quickly smothered due to the rapid capillary action above described. The position of the body of mercury 14 when the circuit is closed is shown in slightly exaggerated form in Fig. 4.

A suggested theory of operation of the device which is believed to be responsible for the desirable results will be outlined in the following paragraph.

When the tube is tilted in the reverse direction for opening the circuit the body of mercury 14 assumes the shape shown in Fig. 5. It will be noted that the surface tension on the mercury tends to cause the body of mercury to stretch or become elongated and thus remain in contact with the electrode 12 slightly longer than it other-

wise would. When the tube becomes sufficiently tilted, however, the surface tension is interrupted and the circuit is broken at this point. After the mercury leaves the electrode 12, its surface tension will again be resumed with a snap action and the surface will then be sufficiently distant from the electrode to cut off any possibility of further arcing. However, if large currents are carried a slight arc will occur at the electrode 12 just as the circuit becomes broken and this arc will, in some cases, be sufficient to volatilize a small amount of the body of mercury 14 and will also volatilize any mercury which would otherwise remain on and serve to keep the electrode 12 in a wetted condition. This will leave the bare and unwetted surface of the electrode 12 exposed so that it is undesirable to permit another arc to occur at this point until the surface is again wetted with mercury. An exposed metallic body in the presence of heated gases is subject to deterioration by molecular bombardment. It will be understood that any volatilization of small amounts of mercury in the tube is not particularly undesirable and such action is preferable to any possible deterioration of the bare electrode surfaces. For these reasons therefore the circuit is made or completed at the electrode 13 and interrupted or broken at the electrode 12. With such a cycle of operations, the arcing, if any, always occurs between the body of mercury 14 and that one of the electrodes 12 or 13, which has last been wetted by contact with the body of mercury. After each arcing occurs, the electrode at that point has an opportunity to become covered with mercury to replace that which has been volatilized before another arc can occur at this point. It is believed that this method of using a moving body of conducting fluid in connection with the electrodes is largely responsible for the success of this form of contactor in circuits where some other types of mercury contactors have failed to operate satisfactorily.

In the modification shown in Figs. 7 and 8, the glass chambers 28 and 29 are both located at considerable distance from the region of the electrodes. The glass chambers in this modification are located at points adjacent the center of the tube for a particular purpose. The modification of Figs. 1 and 2 is especially designed for use with apparatus wherein the tube is tilted only to a comparatively slight angle, whereas the modification of Figs. 7 and 8 is especially designed for use in apparatus such as that in which the tube is tilted to a very large angle, for example in the neighborhood of 90°. In the latter form if the chamber 29 were located at the end of the tube this would result in a great enlarge- 120 125 130 135 140 145 150 155 160 165 170 175 180

4

ment of the space within the tube at this point into which the mercury would flow if the tube were tilted to a large angle. This displacement of the mercury would result in a disconnection of the circuit to the inner electrode 30 unless an excessive amount of mercury were used. It will also be noted that in the modification of Figs. 7 and 8 that the leads to both electrodes 30 and 31 extend 10 for a considerable distance away from the region of the electrodes. With this structure the seals at both of the leads are at a safe distance from the heat at the electrodes. This form of tube therefore is particularly adapted to operate with large currents and to operate satisfactorily even though tilted to a great angle. The electrode 30 is shown tilted a slight amount from the vertical position in order that it 20 may be placed within a tube of the usual diameter and still leave room for the lead to the other electrode 31. It will be noted that the electrode 30 in this modification is also positioned a slight amount above the 25 level of the electrode 31 for the reason above pointed out in connection with the modification of Figs. 1 and 2.

The forms of contactors as above described form a very reliable means for controlling electrical circuits carrying substantial currents at comparatively high voltages without deterioration. Such a device obviously has a great many advantages over any former type of switching mechanism, since 35 very little energy is required to tilt the tube into an out of circuit-making position and at the same time the device is designed to be placed directly in series with the electrical apparatus controlled thereby.

40 While we have shown and described several embodiments of our invention, it is to be understood that many modifications may be made therein without departing from the spirit and scope of the appended 45 claims, and we desire that only such limitations shall be imposed upon our invention as are specifically pointed out in the claims and such as are required by the prior art.

Having thus described our invention, what 50 we claim as new and desire to secure by Letters Patent in the United States, is:—

1. An electrical contactor comprising an hermetically sealed container, electrodes of substantial and concentrated mass contained therein that are spaced remotely from the container walls, a movable contact engaging the lower inner surface of said container and adapted to contact with said electrodes at predetermined times, said container being 55 provided with spaced outwardly expanded chambers, leads for said electrodes entering said container through said chambers and being hermetically sealed therein remotely from said movable contact, said electrodes and from the heat of the arcing that may obtain at said electrodes.
2. An electrical contactor comprising an hermetically sealed container, electrodes of substantial contact-making area and of concentrated mass disposed therein that are 70 spaced from the container walls, a body of conducting fluid engaging the lower surface of said container and adapted to contact with said electrodes at predetermined times, said container being provided on one of its sides with at least one outwardly expanded chamber, a leading-in wire for one of said electrodes entering said container through said outwardly expanded chamber and being hermetically sealed therein at a point 80 remote from the associated electrode, the exterior of said electrodes and the said leading-in wire within said container being made of material that is substantially non-deteriorating under the conditions obtaining 85 within said container.
3. An electrical contactor comprising a hermetically sealed container, electrodes contained therein adjacent a longitudinal axis thereof and spaced from the container walls, 90 a body of conducting fluid engaging the lower inner surface of said container and contacting with said electrodes at predetermined times, leads for said electrodes entering said container through outwardly 95 expanded extensions on the upper side and sealed therein at points remote from said electrodes, the exterior of said electrodes and of said leads within said container being formed of a substantially pure metal unaffected by said body of conducting fluid in 100 the presence of heat.
4. An electrical contactor comprising a hermetically sealed container, electrodes contained therein and spaced from the container walls, a body of mercury for contacting with 105 said electrodes at predetermined times, an outwardly expanded extension chamber on the upper side of said container, a lead for one of said electrodes entering said container through said chamber and sealed in a wall 110 of said chamber remote from the region of said body of mercury and said electrodes.
5. An electrical contactor comprising a hermetically sealed container, electrodes contained therein and spaced from the container walls, a movable contact for contacting with 115 said electrodes at predetermined times, outwardly expanded extension chambers on the upper side of said container at spaced points, leads for said electrodes entering said container through said chambers and sealed in walls of said chambers remote from the region of said electrodes.
6. An electrical contact making device 120 comprising a hermetically sealed container provided on the upper side thereof with at least one integral outwardly expanded exten-

- sion, cooperating electrodes in said container and spaced from the walls thereof, leading-in wires therefor that are sealed in the walls of said container, one of said leading-in wires being sealed in the remote wall of said extension, and a body of conducting fluid engaging the inner lower surface of said container which serves to contact with said electrodes.
10. An electrical contact making device comprising a hermetically sealed container provided at the upper side thereof with spaced integral outwardly expanded extensions, electrodes in said container spaced from the walls thereof, leading-in wires therefor that are severally sealed in the remote walls of said extensions, and a body of conducting fluid engaging the inner lower surface of said container which serves to contact with said electrodes.
15. An electrical switch comprising a hermetically sealed container, a contact making electrode contained therein and spaced from the container walls, a movable body of conducting liquid for contacting with said electrode at predetermined times, a substantially vertically extending shank integral with said container, a leading-in wire for said electrode entering said container through and sealed in said shank remotely from said electrode, and an outwardly expanded extension chamber on the upper side of said container in a position spaced from said electrode and from the normal path of
20. An electrical switch comprising a hermetically sealed container, a contact making electrode contained therein and spaced from the container walls, a movable body of conducting liquid for contacting with said electrode at predetermined times, a substantially vertically extending shank integral with said container, a leading-in wire for said electrode entering said container through and sealed in said shank remotely from said electrode, and an outwardly expanded extension chamber on the upper side of said container in a position spaced from said electrode and from the normal path of
25. An electrical switch comprising a hermetically sealed container, a contact making electrode contained therein and spaced from the container walls, a movable body of conducting liquid for contacting with said electrode at predetermined times, a substantially vertically extending shank integral with said container, a leading-in wire for said electrode entering said container through and sealed in said shank remotely from said electrode, and an outwardly expanded extension chamber on the upper side of said container in a position spaced from said electrode and from the normal path of
30. An electrical switch comprising a hermetically sealed container, a contact making electrode contained therein and spaced from the container walls, a movable body of conducting liquid for contacting with said electrode at predetermined times, a substantially vertically extending shank integral with said container, a leading-in wire for said electrode entering said container through and sealed in said shank remotely from said electrode, and an outwardly expanded extension chamber on the upper side of said container in a position spaced from said electrode and from the normal path of
35. An electrical switch comprising a hermetically sealed container, a contact making electrode contained therein and spaced from the container walls, a movable body of conducting liquid for contacting with said electrode at predetermined times, a substantially vertically extending shank integral with said container, a leading-in wire for said electrode entering said container through and sealed in said shank remotely from said electrode, and an outwardly expanded extension chamber on the upper side of said container in a position spaced from said electrode and from the normal path of
40. An electrical contactor comprising an elongated hermetically sealed glass container, spaced electrodes positioned in one end thereof and spaced from the walls of said container, a body of conducting liquid free to flow from end to end of said container into or out of bridging relation with said electrodes at predetermined times, integrally formed outwardly expanded extension chambers on a side of said container in positions widely spaced from the normal path of flow of said mercury, inwardly extending integral shanks in said chambers, leads for said electrodes entering said container through, and sealed in said shanks at remote points from said electrodes.
45. An electrical contactor comprising a sealed container, an electrode contained therein adjacent one end wall thereof, a second electrode contained therein in proximity of and normally slightly above said first named electrode but at a greater distance from said end wall, both of said electrodes being spaced from the container walls, and a body of conducting liquid free to flow along the bottom of said container into and out of bridging relation with said electrodes at pre-determined times.
50. An electrical contactor comprising a sealed container, an electrode contained therein adjacent one end wall thereof, a second electrode contained therein in proximity of and slightly above said first named electrode but at a greater distance from said end wall, a body of conducting liquid at the bottom of said container for bridging said electrodes at predetermined times, and a lead for said second named electrode entering said container and sealed therein at a point remote from said electrodes.
55. A tiltable electrical contactor comprising a hermetically sealed elongated glass container, electrodes contained therein and spaced from the walls thereof, a body of mercury for contacting with said electrodes, supporting and connecting leads exposed interiorly of said container for said electrodes and composed of a metal substantially unaffected by said mercury in the presence of an electric arc and heat, outwardly expanded extension chambers located at spaced points remote from said electrodes on said container and remote from the normal path of flow of said body of mercury, and inwardly extending integral glass shanks at the outer ends of said extension chambers, said leads entering said container through said shanks and said extension chambers remote from said electrode.
60. A tiltable electrical contactor comprising a hermetically sealed elongated glass container, electrodes contained therein adjacent one end thereof and spaced from the walls of said container, a body of mercury for contacting with said electrodes at predetermined times, supporting and connecting leads for said electrodes composed of a metal substantially unaffected by said mercury in the presence of heat and an electric arc, and outwardly expanded extension chambers located at spaced points on said container and remote from the normal path of flow of said body of mercury, said leads entering said container by being sealed through the upper central portions of said extension chambers whereby said seals are located remotely from said electrodes and said body of mercury.
65. A tiltable electrical switch comprising a hermetically sealed container, cooperating contact making electrodes contained therein and spaced from the walls thereof, a movable body of conducting liquid for contacting with said electrodes at predetermined times, inwardly substantially vertically extending shanks integrally formed with said container, leading-in wires for said electrodes severally entering said container through and sealed in said shanks, and spaced outwardly expanded extension chambers on said container in positions widely spaced from said electrodes and from the normal path of said body of liquid, said

- shanks being largely contained within said extension chambers.
15. An electrical switch comprising a hermetically sealed glass container, cooperating contact making electrodes therein, a movable body of conducting liquid for contacting with said electrodes at pre-determined times, an atmosphere in said container comprising an arc suppressing gas, rods for supporting said electrodes at positions spaced from the glass of said container, said rods extending to the container walls at spaced points that are also widely spaced from the electrodes and from the normal path of the movable body of liquid, leading-in wires attached adjacent the inner surface of the glass walls to said rods and extending outside the container, said liquid, said atmosphere of gas and the surfaces of said electrodes and rods being formed of materials which are substantially inert with respect to each other and in the presence of an electrical arc.
16. An electrical contactor comprising an hermetically sealed container, spaced electrodes of substantial and concentrated mass contained therein and spaced from the container walls, a movable contact for contacting with said electrodes, leading-in wires hermetically sealed in the wall of said container, and supports for said electrodes connected to said leading-in wires, the points of connection between said supports and their respective leading-in wires being embedded in the container wall to preclude exposure of said leading-in wires within the container.

17. An electrical contactor comprising an hermetically sealed container, at least one electrode of substantial and concentrated mass disposed therein, a movable contact for contacting with said electrode, a leading-in wire hermetically sealed in the wall of said container, and a support for said electrode for holding it spaced from the container wall, said support being connected to said leading-in wire and the point of connection between said support and said leading-in wire being embedded in the container wall to preclude exposure of said leading-in wire interiorly of said container.

18. An electrical contactor comprising an hermetically sealed container, an electrode contained therein and spaced from the container wall, a movable contact housed in said container for contacting with said electrode, an outwardly expanded extension chamber formed on a side of the container remote from the path of said movable contact, a leading-in wire entering said container through said extension chamber and hermetically sealed therein remote from said electrode and said movable contact, and a support for said electrode connected to said leading-in wire, the point of connection between said support and said leading-in wire being embedded in the container wall to preclude exposure of said leading-in wire within said container.

In witness whereof, we have hereunto subscribed our names.

LOUIS A. M. PHELAN.
CLIFFORD HOTCHKISS.

shanks being largely contained within said extension chambers.

15. An electrical switch comprising a hermetically sealed glass container, cooperating contact making electrodes therein, a movable body of conducting liquid for contacting with said electrodes at pre-determined times, an atmosphere in said container comprising an arc suppressing gas, 10 rods for supporting said electrodes at positions spaced from the glass of said container, said rods extending to the container walls at spaced points that are also widely spaced from the electrodes and from the normal 15 path of the movable body of liquid, leading-in wires attached adjacent the inner surface of the glass walls to said rods and extending outside the container, said liquid, said atmosphere of gas and the surfaces of 20 said electrodes and rods being formed of materials which are substantially inert with respect to each other and in the presence of an electrical arc.
16. An electrical contactor comprising an 25 hermetically sealed container, spaced electrodes of substantial and concentrated mass contained therein and spaced from the container walls, a movable contact for contacting with said electrodes, leading-in wires 30 hermetically sealed in the wall of said container, and supports for said electrodes connected to said leading-in wires, the points of connection between said supports and their respective leading-in wires being embedded in the container wall to preclude exposure of said leading-in wires within the 35 container.

17. An electrical contactor comprising an hermetically sealed container, at least one electrode of substantial and concentrated 40 mass disposed therein, a movable contact for contacting with said electrode, a leading-in wire hermetically sealed in the wall of said container, and a support for said electrode for holding it spaced from the container wall, said support being connected to said leading-in wire and the point of connection between said support and said leading-in wire being embedded in the container wall to preclude exposure of said leading-in wire interiorly of said container. 45 50

18. An electrical contactor comprising an hermetically sealed container, an electrode contained therein and spaced from the container wall, a movable contact housed in said container for contacting with said electrode, an outwardly expanded extension chamber formed on a side of the container remote from the path of said movable contact, a leading-in wire entering said container through said extension chamber and hermetically sealed therein remote from said electrode and said movable contact, and a support for said electrode connected to said leading-in wire, the point of connection between said support and said leading-in wire being embedded in the container wall to preclude exposure of said leading-in wire within said container. 55 60 65

In witness whereof, we have hereunto subscribed our names. 70
